HEATING SYSTEM

Moritz L. Mueller, Seattle, Wash.

Application October 18, 1944, Serial No. 559,282

9 Claims. (Cl. 237—2)

1
This invention relates to heating systems.

A principal object of the invention is to provide a heating system for dwellings and the like which is particularly adapted to supply heated air to the space in the dwelling by forced circulation and by thermosiphonic flow, the thermosiphonic flow being operable upon cessation of the forced circulation.

Another object of the invention is to provide a new and improved heating system which is simple in construction, efficient in operation, and relatively inexpensive in cost so that it may be made available for use in connection with small and/or low-priced dwellings.

Other objects and advantages of the invention will be apparent from a consideration of the following specification taken in conjunction with the accompanying drawings, of which there is one sheet and wherein:

Fig. 1 is a vertical sectional view through a house illustrating, somewhat diagrammatically, my new and improved heating system;

Fig. 2 is an enlarged fragmentary view of a part of the system illustrated in Fig. 1; and

Fig. 3 is a diagrammatic view of the circuit for the blower motor.

The house may include a basement 10, space 12 to be heated and adapted to serve as living quarters, and an attic space 14 thereabove. A chimney 16 of masonry or other suitable construction extends upwardly from its base to and above the roof 18 of the building and provides an atmospheric vent 20 for the products of combustion. A combustion chamber 22 may be arranged in the base of the chimney and have associated with it suitable means 23 for burning fuel so as to generate heated products of combustion.

A tubular heat exchanger member 24 is arranged in said chimney 16 and in spaced relation with the walls thereof, the heat exchanger member 24 at its lower end being arranged so as to receive the heated products of combustion generated in the combustion chamber 22 and to conduct the same upwardly, the interior of the heat exchanger member 24 forming part of a path for conducting the products of combustion from the combustion chamber to the atmospheric vent 20.

The heat exchanger member 24 at its upper end may terminate short of the top of the chimney 16 and a baffle or plate 26 is provided so as to separate the space externally of the heat exchanger member 24 and therebelow from the space above the heat exchanger member 24.

2
which forms a part of the path for conducting flue gases to atmosphere.

The heat exchanger member 24 and chimney 16 cooperate to provide countercurrent heat exchange paths for the upward flow of the products of combustion and the downward flow of air to be heated, one of the paths surrounding the other. A motor driven blower 28 has its outlet end arranged to deliver air into the upper end of the air path 30 and under a pressure greater than that of the products of combustion within the heat exchanger member 24. The blower 28 is arranged to be driven by a motor 32, the circuit of which is controlled by a thermostatic switch 34 the bimetallic element 36 of which is positioned in the flue passageway just above the heat exchanger member 24.

The blower 28 has its inlet connected to one end of a return air duct 38 which extends across 20 the ceiling and downwardly between the studding of the walls of the house, the other end of the return air duct 38 terminating in an opening 40 communicating with the space 12 for withdrawing air to be heated therefrom during the operation of the blower 28.

The thermostatic switch 34 may be set so as 30 close the motor circuit when the temperature of the flue products issuing from the upper end of the heat exchanger member 24 attains a predetermined degree, say for example 225 degrees F., and to open such motor circuit when the temperature of such gases drops to a predetermined degree, say for example a temperature of 200 degrees F.

The lower end of the air path 30 may be formed 35 by a tubular pipe 42 which surrounds the lower end of the heat exchanger member, the lower end of such pipe 42 forming an annular outlet from the air path for the air which has been heated by its passage therethrough. The space between the pipe 42 and the lower end of the chimney, which may be enlarged, in effect constitutes a plenum chamber from which one or more hot air ducts 44 conduct heated air to openings 46 which discharge heated air into the space 12 to be heated. Such number of ducts 44 and outlets 46 may be provided so as to obtain the desired distribution of heated air during the operation of the system.

Thus, in the system as described, when the rate at which heated products of combustion are being generated in the combustion chamber 22 is sufficiently high, the blower 28 will be caused to operate and circulate air from the space to be heated through the ducts 38, air path 30 and

ducts 44 for supplying heated air to such space.

The fuel burning means may be of the type disclosed in my application Serial No. 427,734, filed January 22, 1942, for "Heating apparatus," now Patent No. 2,348,834, and for such fuel burning means any of the control arrangements illustrated in such patent or any other desired control arrangement may be employed. Preferably the fuel burning means may be of the type in which the heat output may be modulated so as to provide a system of some flexibility and to provide various rates of heat generation for different temperature conditions.

The system further includes provisions by means of which heat may be generated and supplied to the space 12 when the blower 28 is not operating. These provisions include a gravity cold air return 50, one end of which communicates with the space 12 and the other end of which opens into the air path 30 below the pipe 42. The communication between the cold air return 50 and the lower end of the air path 30 is adapted to be closed during operation of the blower by a gravity damper 52 pivoted at 54. The area of the damper 52 below the pivot 54 is greater than that of the damper 52 above the pivot 54 so that during the operation of the blower 28 the pressure in the air path 30 will keep the damper 52 closed. A weight 56 mounted on the damper above the pivot 54 is adapted to cause the damper to swing in a counterclockwise direction when the blower 28 stops so as to establish communication between the cold air duct 50 and the lower end of the air path 30, the damper at such time being adapted to assume a horizontal position.

A damper-controlled vent 60 is also provided in the wall of the chimney 16 at an elevation materially above the damper 52. This vent 60 is also adapted to be closed during the operation of the blower 28 by a damper 62 pivoted at 64. The area of the damper 62 below the pivot 64 is materially greater than the area of the damper above the pivot 64 so that during the operation of the blower 28 the pressure of the air in the air path 30 will position the damper 62 so as to close the vent 60. The damper 62, however, is provided with a weight 66 which is adapted when the blower 28 stops to cause the damper 62 to pivot in a clockwise direction so as to open the vent 60 and establish communication between the air path 30 and the space 12 to be heated. Thus, when the blower 28 stops, the dampers 52 and 62 will open, and if the heat exchanger member 24 is heated, thermosiphonic flow of air downwardly through the cold air return 50, upwardly through the air path 30, and out into the space 12 through the vent 60 will be provided.

In this way, the system is adapted to supply heat to the space 12 to be heated under gravity circulation when the blower 28 stops. This not only provides for a continuous supply of heat to the space to be heated during the operation of the fuel burning means, but also provides a safety feature so as to dissipate heat from the heat exchanger member 24 in the event the blower 28 stops in the event of current failure or otherwise when the switch 34 is closed. With this arrangement the wide fluctuations in temperature commonly experienced in forced air heating systems when the blower operates intermittently will be eliminated.

While the invention has been described with some detail, it is to be understood that the description is for the purpose of illustration only

and is not definitive of the limits of the inventive idea. The right is reserved to make such changes in the details of construction and arrangement of parts as will fall within the purview of the attached claims.

I claim:

1. In a heating system having a vertical air passageway provided with an air inlet at the upper end thereof connected to the space to be heated for supplying air therefrom to said passageway to be reheated and an air outlet at the lower end of said passageway connected to the space to be heated for supplying heated air thereto, a blower associated with the inlet end of said passageway and operable for effecting the forced circulation of air therethrough, an elongated heat exchanger member exposed to the air in said passageway for heating the same, a combustion chamber having fuel burning means associated therewith operable for supplying heated products of combustion to said heat exchanger member, an electric motor for driving said blower, a thermostatic switch positioned so as to be responsive to the temperature of said products of combustion adjacent the upper end of said heat exchanger member and operable for closing the motor circuit when the temperature of the combustion products reaches a predetermined degree and for opening the motor circuit when the temperature thereof falls to a predetermined degree, said passageway being provided adjacent the upper end thereof with a damper-controlled outlet communicating with said space to be heated, means for automatically closing said damper-controlled outlet upon operation of said blower and for automatically opening said damper-controlled outlet upon stoppage of said blower, and a cold air return from said space to the lower end of said passageway, said cold air return being provided with normally open damper, and means for automatically closing said cold air return damper upon operation of said blower.

2. Heating apparatus comprising means defining a path for the thermosiphonic flow of air to be heated and including a vertically extending portion, heat exchanger surface arranged in said vertically extending portion in the thermosiphonic path of flow of the air to be heated and adapted when heated to effect a gravity circulation of air to be heated through said heating apparatus, said apparatus being constructed to provide free ingress of air to be heated to said path and free egress of heated air from said path when said surface is heated, means defining another path for flow of air through said apparatus, said second path including that part of said first path having said heat exchanger surface arranged therein, means for effecting a forced circulation of air through said second path, other heat exchanger surface in said second path in addition to the heat exchanger surface exposed to thermosiphonic flow in said first path, all of said heat exchanger surface being arranged for heating the air in its flow through said second path, said means defining said second path, said forced air circulating means and said last mentioned heat exchanger surface being arranged in such a manner as not to materially interfere with the gravity circulation of air through said first mentioned path, said heat exchanger surfaces being arranged on the discharge side of said forced air circulating means, both of said paths at each end thereof being connected to the same space to be heated in such manner that the air which circulates through

both of said paths is circulated through the said space.

3. Heating apparatus comprising means defining a path for the thermosiphonic flow of air to be heated and including a vertically extending portion, heat exchanger surface arranged in said vertically extending portion in the thermosiphonic path of flow of the air to be heated and adapted when heated to effect a gravity circulation of air to be heated through said heating apparatus, said apparatus being constructed to provide free ingress of air to be heated to said path and free egress of heated air from said path when said surface is heated, means including the vertically extending portion of the aforementioned path defining another path for flow of air through said apparatus, means for effecting a forced circulation of air through said second path, heat exchanger surface in said second path in addition to that exposed to thermosiphonic flow in said first path, all of said heat exchanger surface being arranged for heating the air in its flow through said second path, said means defining said second path, said forced air circulating means and said last mentioned heat exchanger surface being arranged in such a manner as not to materially interfere with the gravity circulation of air through said first mentioned path, said heat exchanger surfaces being arranged on the discharge side of said forced air circulating means, and means for preventing the ingress of air to and the egress of air from said first mentioned path during operation of said forced air circulating means.

4. A heating system comprising a vertical air passageway having an air inlet at the upper end thereof connected to the space to be heated for supplying air therefrom to said passageway to be reheated and an air outlet at the lower end of said passageway connected to the space to be heated for supplying heated air thereto, a blower associated with the inlet end of said passageway and operable for effecting the forced circulation of air therethrough, a heat exchanger member exposed to the air in said passageway, a combustion chamber having fuel burning means associated therewith operable for supplying heated products of combustion to said heat exchanger member, said passageway being provided adjacent the upper end thereof with a damper-controlled outlet communicating with said space to be heated, means for automatically closing said damper-controlled outlet upon operation of said blower and for automatically opening said damper-controlled outlet upon stoppage of said blower, and a cold air return from said space to the lower end of said passageway, said cold air return being provided with a normally open damper, and means for automatically closing said cold air return damper upon operation of said blower.

5. A heating system comprising a vertical air passageway having an air inlet at the upper end thereof connected to the space to be heated for supplying air therefrom to said passageway to be reheated and an air outlet at the lower end of said passageway connected to the space to be heated for supplying heated air thereto, a blower associated with the inlet end of said passageway and operable for effecting the forced circulation of air therethrough, a heat exchanger member exposed to the air in said passageway, a combustion chamber having fuel burning means associated therewith operable for supplying heated products of combustion to said

heat exchanger member, said passageway being provided below the upper end of said heat exchanger member with a damper-controlled outlet communicating with said space to be heated, means for automatically closing said damper-controlled outlet upon operation of said blower and for automatically opening said damper-controlled outlet upon stoppage of said blower, and a cold air return from said space to the lower end of said passageway, said cold air return being provided with a normally open damper, and means for automatically closing said cold air return damper upon operation of said blower.

6. In a heating system having a vertical air passageway provided with an air inlet at the upper end thereof connected to the space to be heated for supplying air therefrom to said passageway to be reheated and an air outlet at the lower end of said passageway connected to the space to be heated for supplying heated air thereto, a blower associated with the inlet end of said passageway and operable for effecting the forced circulation of air therethrough, an elongated heat exchanger member exposed to the air in said passageway for heating the same, a combustion chamber having fuel burning means associated therewith operable for supplying heated products of combustion to said heat exchanger member, an electric motor for driving said blower, a thermostatic switch positioned so as to be responsive to the temperature of said products of combustion adjacent the upper end of said heat exchanger member and operable for closing the motor circuit when the temperature of the combustion products reaches a predetermined degree and for opening the motor circuit when the temperature thereof falls to a predetermined degree, means including a part of the aforementioned passageway defining a path for the thermosiphonic flow of air from said space to be heated and back to said space, and means for preventing the ingress of air to and the egress of air from said path during operation of said blower.

7. A heating system comprising a vertical air passageway having an air inlet at the upper end thereof connected to the space to be heated for supplying air therefrom to said passageway to be reheated and an air outlet at the lower end of said passageway connected to the space to be heated for supplying heated air thereto, a blower associated with the inlet end of said passageway and operable for effecting the forced circulation of air therethrough, a heat exchanger member exposed to the air in said passageway, a combustion chamber having fuel burning means associated therewith operable for supplying heated products of combustion to said heat exchanger member, means including a part of the aforementioned passageway defining a path for the thermosiphonic flow of air from said space to be heated and back to said space, and means for preventing the ingress of air to and the egress of air from said path during operation of said blower.

8. Heating apparatus comprising means defining a path for the thermosiphonic flow of air to be heated and including a vertically extending portion, heat exchanger surface arranged in said vertically extending portion in the thermosiphonic path of flow of the air to be heated and adapted when heated to effect a gravity circulation of air to be heated through said heating apparatus, said apparatus being constructed to provide free ingress of air to be heated to said path and free

egress of heated air from said path when said surface is heated, means including said vertically extending portion of the aforementioned path defining another path for flow of air through said apparatus, means for effecting a forced circulation of air through said second path, heat exchanger surface in said second path in addition to that exposed to thermosiphonic flow in said first path, all of said heat exchanger surface being arranged for heating the air in its flow through said second path, said means defining said second path, said forced air circulating means and said last mentioned heat exchanger surface being arranged in such a manner as not to materially interfere with the gravity circulation of air through said first mentioned path, said heat exchanger surfaces being arranged on the discharge side of said forced air circulating means, and means operable upon operation of said forced air circulating means for closing the inlet and outlet to said first mentioned path.

9. Heating apparatus comprising means defining a path for the thermosiphonic flow of air to be heated and including a vertically extending portion, heat exchanger surface arranged in said vertically extending portion in the thermosiphonic path of flow of the air to be heated and adapted when heated to effect a gravity circulation of air to be heated through said heating apparatus, said apparatus being constructed to provide free ingress of air to be heated to said path and free egress of heated air from said path when said surface is heated, means including said vertically extending portion of the aforementioned path defining another path for flow of air through said apparatus, a blower operable for effecting a forced circulation of air through said second path, heat exchanger surface in said second path in addition to that exposed to thermosiphonic flow
